UNITED STATES PATENT OFFICE

ROBERT D. DUNCAN, JR., OF EAST ORANGE, NEW JERSEY, ASSIGNOR TO WIRED RADIO, INC., OF NEW YORK, N. Y., A CORPORATION OF DELAWARE

SYSTEM OF ELECTRICAL DISTRIBUTION

Application filed June 7, 1930. Serial No. 459,785.

My invention pertains in general to electrical distribution systems and specifically relates to an electric power and light distribution system in which there is minimum attenuation offered to the transmission of alternating currents of high frequency, such as wires radio signals.

In wired radio broadcasting or communication by means of modulated high frequency currents over electric light and power lines, it has been determined by actual operation that the light and power lines may have appreciable attenuation effects for the passage of high frequency currents. Such attenuation is brought about in part by the absorption of high frequency power by the lines, and in part by the absorption of high frequency power by ordinary power equipment such as transformers, heating elements, lamps, et cetera, which are connected across the lines. Certain sections of a light and power distribution system, such as the secondaries extending from distribution transformers to the consumer's local distribution circuits, generally offer greater attenuation than other sections of the distribution system.

One of the objects of my invention consists in providing means for substantially eliminating excessive high frequency attenuation which electric light and power distribution systems offer to the transmission of high frequency currents.

Another object comprises providing independent wire lines between a light and power substation and a subscriber's premises over which high frequency currents are transmitted.

A further object consists in providing a combined electric light and power high frequency distribution system and means for utilizing the subscriber's house wiring system as a common means of local distribution of light and power and high frequency currents.

A still further object comprises producing a distribution system in which light and power currents and high frequency currents are independently distributed to a certain

point and at that point combined upon a common distribution system.

I accomplish the above desirable features in a novel system of electrical distribution for electric light and power lines in which additional and independent lines are provided for the transmission of high frequency currents to the consumer's premises where the said high frequency currents are impressed on the consumer's local light and power distribution lines in a manner such that both power and light and high frequency signals are available at any of the consumer's outlet sockets.

In the drawing accompanying and forming a part of this specification and in which like reference numerals designate corresponding parts throughout; I have schematically illustrated one embodiment of my invention.

Referring to the drawing, a source of light and power current 1 is situated in a substation 2. This source of light and power current may be either a power generator or transforming equipment. Lines 3 extend from the light and power source 1 and to step-down transformers 4 and 5. The transformers 5 and 4 supply proper voltages through secondary lines 6 and 7 for consumer's dwellings 8 and 9, respectively. It is to be understood that the illustration of these transformers is merely representative of a secondary supply system. In actual practice, one transformer could serve several dwellings and could be situated some distance from the dwellings. Service switches 10 and 11 are interposed in the consumer's local distribution circuits 6 and 7, respectively. A watthour meter 12 and fuse box 13 are provided in the local distribution circuit 6 and comprise normal service equipment of a consumer's dwelling. The watthour meter 14 and fuse box 15 are also provided in the local distribution system 7 of the consumer's dwelling 9.

In the substation 2 I provide an oscillator 16, a modulator 18 and an amplifier 17 all of which comprise a source of modulated high frequency signals. It is obvious that such source of high or radio frequency signals is situated in the substation 2 merely as a mat-

ter of convenience, and could equally well be situated at any other point. Lines 19 extend from the modulator 18 and are adapted to carry high frequency signals. These lines 5 19 may be co-extensive with the power lines 13 or may be provided only in certain sections of the power distribution system where disturbing attenuation effects are particularly pronounced. In my invention I provide lines 20 connected to the lines 19 and 10 capacitatively coupled to the local distribution lines 7 of the consumer's dwelling 9 by means of condensers 21 and 22. These condensers 21 and 22 offer relatively low impedance 15 to the passage of high frequency currents and high impedance to the passage of low frequency and direct currents.

A signal blocker 23 comprising a choke coil 24 is in series with one of the lines 7 extending 20 from the step down transformer 4. The choke coil 24 is essentially an inductance which blocks high frequency currents.

A similar arrangement is provided in the consumer's dwelling 8 wherein lines 25 extend 25 from the supply lines 19 to condensers 26 and 27, and signal blocker 28 comprising a choke coil 29 is interposed in the line 6 extending from the step down transformer 5.

The capacitative coupling between the 30 high frequency lines and the consumer's distribution system may be connected to any point of the consumer's local distribution system. It will be noted that the condensers 21 and 22 are connected into the lines 35 7 between the signal blocker 23 and the service switch 11 in dwelling 9, whereas the condensers 26 and 27 are connected to the lines 6 between the watthour meter 12 and the fuse box 13 in dwelling 8. These two 40 examples illustrate two different methods of tying in radio frequency lines to the consumer's distribution circuit which could be used to meet varying conditions of consumer's wiring installation. The method of connection 45 in the dwelling 8 has a particular advantage in that the field coils of the watthour meter 12 being in series with the choke coil 29 tend to increase the effectiveness of the choke coil in blocking high frequency currents.

For convenience of operation, it is highly desirable that wired radio receivers may be connected to any service outlet of the consumer's dwelling so that the receiver can receive 55 radio frequency signals as well as tube filament and plate operating voltages from one outlet. The receiver 28 is connected to the local distribution lines 6. Normal means are provided within the receiver 28 for receiving 60 radio frequency signals in the line 6 by capacitative couplings and at the same time supplying necessary tube operating voltages by direct connections to the lines 6. A similar receiver 29 is provided in the consumer's dwelling 9 and is connected to the

local distribution lines 7 thereof. It is obvious that any number of such receivers may be provided in the consumer's dwelling for the reception of wired radio signals.

High frequency signals upon being impressed 70 by the modulator 18 on the lines 19 are individually distributed to the consumer's local distribution lines by means of the auxiliary lines 20 and 25 which extend from the high frequency lines 19. The condensers 21 75 and 22, and 26 and 27 serve as means for impressing the radio frequency currents on the local distribution lines of the consumer's dwellings as hereinbefore described. Since these condensers offer high impedance to low 80 frequency and direct currents, the electric light and power currents carried on the secondary lines 6 and 7 and derived from the primary high tension line 3 will be prevented from feeding back into the high frequency 85 lines 19. The blockers 23 and 28 in the secondary lines 7 and 6, respectively, will effectively prevent the feeding back of high frequency current into the electric light and power distribution system. The distribution 90 of high frequency currents on the electric light and power lines is, therefore, confined to the local distribution lines of the consumer's dwelling. It is, of course, obvious that the blockers 23 and 28 may be located somewhat 95 removed from the consumer's dwelling, as for example, in the immediate vicinity of the step down transformers 5 and 4 without departing from the scope of my invention. Also, it will be obvious that one blocker, such as blocker 28 might be utilized in a secondary distribution line serving several dwellings and, therefore, confine the high frequency distribution to secondary lines serving a 100 group of consumers.

It will be apparent that the system herein described offers a satisfactory means of overcoming disturbing attenuation effects to be found in light and power distribution networks, and at the same time is of special advantage in that the normal operation of wired radio receiver from any electric light and power service outlet of the consumer's dwelling is permitted.

While I have shown but two consumer's dwellings in association with an electric light and power substation, it will, of course, be readily understood that my electrical distribution system as hereinbefore described is readily applicable to any number of consumers served by electric light and power lines from any source. I do not, therefore, wish to be limited in my invention except insofar as may be pointed out in the appended claims.

I claim:

1. In an electrical distribution system, a local distribution circuit confined within a consumer's premises, a source of electric light and power current, wire lines adapted to de- 130

- liver said light and power current to said local distribution circuit in said consumer's premises, a source of modulated high frequency current, wire lines adapted to deliver
- 5 said modulated high frequency current to said consumer's premises, and means adapted to impress said high frequency currents on said local distribution circuit in said consumer's premises only.
- 10 2. In an electrical distribution system, a local distribution circuit within a consumer's premises, a source of commercial power including a substation, power lines for delivering commercial power from said substation
- 15 to said local distribution circuit in said consumer's premises, a source of modulated high frequency current, other wire lines for delivering said modulated high frequency to said consumer's premises, coupling means between
- 20 said wire lines and said consumer's circuit for impressing said high frequency current thereon, and means connected in said local distribution circuit for restricting said high frequency current thereto.
- 25 3. In a system of electrical distribution, a power substation for supplying high voltage commercial power, a plurality of consumer's circuits, power transformer equipment remotely situated from said substation but connected therewith by power lines for supplying commercial power at reduced voltages to said consumer's circuits, wire lines independent of said power lines and extending from said substation to said consumer's circuits,
- 35 means including an amplifier in said substation for supplying high frequency current to said wire lines, coupling means between said wire lines and said consumer's circuits for supplying high frequency current there-
- 40 to, and means connected in said consumer's circuits for restricting said high frequency current thereto.
4. In a system of electrical distribution, a power substation for supplying high voltage commercial power, a local distribution circuit confined within a consumer's premises, power transformer equipment remotely situated from said substation but connected thereto by power line for supplying commercial power at reduced voltages to said consumer's circuits, means in said substation for amplifying modulated high frequency current, means independent of said power lines for transmitting modulated high frequency
- 50 current from said substation to said consumer's premises, means adapted to impress said high frequency current on said local distribution circuit in said consumer's premises, and means for substantially preventing the pas-
- 55 sage of said high frequency currents from said local distribution circuit to said power lines.
- 60 5. In an electrical distribution system, a local distribution circuit confined within a consumer's premises, a power substation for
- 55 supplying high voltage commercial power, power transformer equipment remotely situated from said substation but connected therewith by power lines for supplying commercial power at reduced voltages to said local distribution circuit in said consumer's premises, a source of modulated high frequency current, means independent of said power lines and said transformer equipment for delivering said modulated high frequency current to said consumer's premises, and means adapted to impress said high frequency currents on said local distribution circuit in said consumer's premises only.
- 70 6. In an electrical distribution system, a local distribution circuit confined within a consumer's premises, a power substation for supplying high voltage commercial power, power transformer equipment remotely situated from said substation but connected therewith by power lines for supplying commercial power at reduced voltages to said local distribution circuit in said consumer's premises, a source of modulated high frequency current, wire lines adapted to deliver
